UNITED STATES PATENT OFFICE.

LEWIS B. DOMAN, OF ELBRIDGE, NEW YORK.

WIND-INDUCING DEVICE FOR SELF-PLAYING MUSICAL INSTRUMENTS.

1,073,223.

Specification of Letters Patent. Patented Sept. 16, 1913.

Original application filed August 8, 1906, Serial No. 329,692. Divided and this application filed November 20, 1906. Serial No. 344,214.

To all whom it may concern:

Be it known that I, LEWIS B. DOMAN, of Elbridge, in the county of Onondaga, in the State of New York, have invented new and useful Improvements in Wind-Inducing Devices for Self-Playing Musical Instruments, of which the following, taken in connection with the accompanying drawings, is a full, clear, and exact description.

10 This invention relates to certain improvements in wind inducing devices for self-playing musical instruments and it is specially adapted for what is commonly known as inside players of the class set forth in my 15 pending application No. 329,692, filed August 8th, 1906, of which the present application is a division.

The particular object which I have sought to carry out is to permanently combine and 20 unite all of the elements of the wind inducing device including the exhaust bellows, wind-chest, equalizing chamber and pedal action in a single article of manufacture, capable of being installed within the case of 25 a piano or similar instrument to be used in connection with various forms of self-playing musical instruments. In other words, I have permanently mounted the exhausting and equalizing bellows and also the pedal 30 frame directly upon a wind chest having suitable leads to which flexible tubes may be attached for connection with the sound producing action and pneumatic motor.

A further object is to mount pedals upon 35 a swinging frame adapted to be folded, when not in use, upwardly, flatwise against the front face of the wind-chest.

Other objects and uses will be made apparent in the following description.

40 In the drawings, Figures 1 and 2 are similar transverse sectional views of my improved wind inducing device, the swinging pedal frame and pedals being shown in operative position in Fig. 1 and folded to 45 their inoperative position in Fig. 2. Fig. 3 is a longitudinal sectional view of the same device taken on line 3-3 Fig. 1.

As shown in the drawings this wind inducing device comprises a wind-chest —1—, 50 a pair of exhaust bellows —2—, an equalizing bellows —3— and suitable operating pedals —4— having their forward ends pivoted at —5— to the front end of a vertically swinging frame —6—, and their rear ends 55 connected by links —7— to forwardly pro-

jecting arms —8— which are secured to the movable sides of the exhaust devices —2—. The wind-chest —1— preferably consists of comparatively long front and rear rectangular boards —10— and —11— arranged edgewise vertically and spaced apart by comparatively narrow strips —12— of wood and additional strips —13— of comparatively thick cardboard or paper, said strips being adhesively secured to each other 60 and to and between the marginal edges of the front and rear boards —10— and —11— forming an intervening air chamber —14— which is comparatively shallow transversely but nearly co-extensive with the area of the 70 wind-chest.

The wood strips —12— are adhesively secured to the front face of the back piece —11— and the pasteboard or paper strips —13— are adhesively secured to the front 75 face of the strips —12— and to the rear face of the front board —10— forming a yielding connection between the front and back boards which allows a limited "come and go" for shrinkage and expansion without liability of opening the joint between the front and back board, and at the same time affording a means by which the front board may be separated from the back board without splitting or otherwise injuring the 85 wood parts because the paper may be more readily split between its glued surfaces, whereas, if the wood surfaces were glued together it would be quite impossible to separate them without splitting the wood. 90

This idea of interposing pasteboard or thick paper between the contiguous wood parts serves not only to prevent leakage, by imperfect or strained joints, but also enables the wood parts of the wind-chest to be 95 separated without destroying them should it become necessary to open the wind-chest, under which conditions the split pasteboard adhering to the sides of the wood could be readily scraped off by moistening, and new 100 strips of paper substituted when re-assembling the wood parts.

The exhaust devices —2— are secured side by side in upright positions to the central portion of the rear faces of the back board 105 —11— of the wind-chest —1—, their rear sides being movable through the medium of their respective pedals —4— and connections —7— and —8—. The inner side of each bellows communicates through suitable ports 110

—15— with the chamber —14— of the wind-chest. These ports are each provided with a suitable valve —16— opening into the bellows —2— to allow the passage of 5 the air from the wind chest —1— into said bellows. In like manner the rear movable wall of each bellows is provided with ports —17— having a valve —18— opening outwardly to allow air to pass from bellows to 10 atmosphere but prevents reentrance of such air into the bellows. Each bellows —2— is provided with one of the brackets or arms —8— which brackets extend forwardly under the bellows and wind-chest and have 15 their forward ends pivotally connected to one end of the links —7—.

The front end of each pedal is pivoted to a common metal bar —20— constituting a part of the swinging frame —6—, said bar 20 extending under and some distance beyond the side edges of the pedals and has its opposite ends rigidly secured to rearwardly projecting arms or bars —21—. These bars —21— are located at the outer sides of the 25 pedals and their rear ends are pivoted at —22— to suitable brackets —23— on the front board of the wind-chest —1—, said pivots —22— constituting the swinging axis for the pedal supporting frame —6— and 30 are located nearly in line with the bottom of the wind-chest and in proximity to the pivotal connection between the links —7— and arms —8—.

The whole device is adapted to be mounted 35 upon a suitable rail as —A— with which the base of all piano cases is usually provided and for this purpose I provide suitable metal feet —25— which are, in this instance, secured to the front sides of the 40 bellows —2— and are adapted to rest upon and be secured to the rail —A—, thereby, supporting the wind-chest and bellows some distance above the floor line upon which the bar —20— is adapted to rest. This wind- 45 chest —1— is provided near its ends with ports —26— and —27— communicating with suitable leads —28— and —29— adapted to be connected to other parts of the 50 self-playing musical instrument as, for instance, a sound producing action and motor action respectively, neither of which are shown because they form no part of my present invention.

The equalizing bellows —3— is secured to 55 the front board —10— near the wind-chest and communicates through a suitable port —30— with said wind-chest, said equalizing bellows —3— being normally distended by a comparatively stiff spring —31—, the object of said equalizing bellows being to 60 maintain a uniform air tension in the pneumatic system, which the wind inducing device is adapted to operate. Secured to the central portion of the front board —10— is 65 an upright bar —33— to the upper end of

which is secured a spring catch —34— for engaging the bar —20— when swung upwardly and retaining the frame —6— together with the pedals —4— and link —7— when in upright position as shown in Fig. 2. 70 The distance between the swinging axis —22— and active portion of the catch —34— is substantially equal to or slightly greater than the distance between said axis and inner face of the bar —20— so that 75 when the frame is rocked upwardly as described, the bar —20— rides upon and slightly depresses the catch —34— and frictionally holds the frame —6— in its upright position. Each pedal —4— and its link —7— forms a toggle connection between the bar —20— and movable side of the bellows —2— so that when the joint between the 80 pedal and link is flexed upwardly in its normal position as shown in Fig. 1, the depression of the pedal —4— by the foot causes the toggle to straighten out and thereby force the movable side of the bellows —2— rearwardly. This operation of the bellows causes the valve —18— to close the 85 ports —17— against atmosphere and at the same time open the valve —16— to exhaust the air from the chamber —14— and equalizing bellows —3— thereby tending to collapse the equalizing bellows —3— against 90 action of its distending spring —31— so that if the pedal action should temporarily cease the action of the equalizing bellows —3— by its spring —31— would operate to 95 temporarily maintain a nearly uniform tension in the system.

What I claim is:

1. A wind inducing device for self-playing musical instruments comprising a bellows having its movable member provided 105 with an arm projecting forwardly under the lower edge thereof, means for supporting the bellows wholly from the lower edge of its stationary side, a wind chest supported wholly by the stationary side of the bellows 110 and communicating therewith, a pedal, a link having one end pivoted to the toe end of the bellows and its other end pivoted to the forward end of said arm, a bar pivotally connected to the heel end of the pedal, and 115 a separate bar having its front end rigidly connected to the first-named bar and its rear end pivotally connected to the wind chest.

2. A wind inducing device for self-playing musical instruments comprising a bellows 120 having its movable member provided with an arm projecting forwardly under the lower edge thereof, means for supporting the bellows wholly from the lower edge of its stationary side, a wind chest supported 125 wholly by the stationary side of the bellows some distance above said arm, an equalizer supported wholly by the wind chest, a pedal, a link pivotally connected to the toe end of the pedal and to the front end of said arm 130

- to swing upwardly and rearwardly, a bar pivotally connected to the heel end of the pedal, and a separate bar of greater length than the link having its forward end rigidly
5 connected to the first named bar and its rear end pivotally connected to the wind chest near the lower edge thereof, and yielding means for engaging the first named bar and holding it in its inoperative position.
- 10 3. A wind-inducing device for self-playing musical instruments comprising a wind-chest, a bellows, and an equalizer, all of such parts being secured together, feet secured to

the fixed side of the bellows and constituting the only means of support for the entire 15 wind-inducing device, and a folding bellows-operating means connected to and supported wholly by portions of the first named parts.

In witness whereof I have hereunto set 20 my hand this 13 day of November, 1906.

LEWIS B. DOMAN.
